UNITED STATES PATENT OFFICE.

LEE S. CHADWICK, OF SHAKER HEIGHTS, OHIO, ASSIGNOR TO PERFECTION STOVE COMPANY, OF CLEVELAND, OHIO, A CORPORATION OF OHIO.

FUEL SYSTEM FOR OIL BURNERS.

Application filed March 21, 1924. Serial No. 700,767.

This invention relates to the class of liquid fuel burners wherein the burner is supplied with fuel from a reservoir sustained at such an elevation that the fuel is fed by gravity 5 to the burner, the reservoir comprising, in the type of apparatus to which my invention more especially pertains, a container—as for example, a glass bottle—that is inverted over a distributing receptacle wherein the 10 liquid fuel accumulates in such quantity as to seal the mouth of the container or bottle, the liquid level in the receptacle determining approximately what the liquid level in the burner shall be. Any marked deviation 15 from this level in the burner results in unsatisfactory operation, and in case the level rises considerably above normal there is danger of the fuel flooding or overflowing the burner with the liability of serious 20 consequences.

In stoves and like apparatus incorporating burners and fuel supply systems of the class described, considerable difficulty has been experienced from the stoves or apparatus being stood upon supports or floors 25 which were not level or substantially so. A slight inclination is not serious, but in some instances where trouble has been reported it has been found that the apparatus 30 is inclined at a grade of approximately two inches in the length of the ordinary stove. The primary purpose of my invention is to obviate the above mentioned difficulty by providing an overflow on each side of the 35 burner in the direction in which the reservoir is spaced from the burner so that in case the stove or apparatus is tilted materially in said direction the liquid fuel will escape from the system at a point remote from the 40 burner and thus avoid the liquid level rising within the burner to a danger point or above the maximum fuel level therein.

A further object of the invention is to incorporate in the apparatus means for 45 conveniently draining the fuel system.

A still further object of the invention is to provide an attachment for stoves and apparatus of the nature above described 50 through which the foregoing objects are attained, and in addition thereto, through which the fuel capacity of the stove or apparatus is materially increased.

Further and more specific objects relating 55 to structural improvements, and resulting in efficiency, strength, durability, depend-

ability, economy and simplicity, will become apparent as this description proceeds, reference being had to the accompanying drawings wherein Fig. 1 is a front elevation of a liquid fuel stove incorporating one form of 60 my invention; Fig. 2 is a repetition of the left hand end of Fig. 1 showing a modification of the invention; Figs. 3 and 4 are left hand end elevations of the embodiments shown, respectively, in Figs. 1 and 2; Fig. 65 5 is a section on the line 5—5 of Fig. 3; Fig. 6 is an enlarged fragmentary longitudinal section through the auxiliary fuel reservoir attachment shown in Figs. 1, 3 and 5; Fig. 7 is a sectional detail of a modified form of 70 connection between the auxiliary fuel reservoir and the fuel supply pipe of the stove; Fig. 8 is a sectional detail on the line 8—8 of Fig. 4; Fig. 9 is a similar view showing a 75 modified form of joint, and Fig. 10 is a 80 perspective view of a bracket employed in the modified form of the invention illustrated in Figs. 2, 4, 8 and 9.

The invention is applicable to liquid fuel stoves, ranges, water heaters and like apparatus, and I have elected to show it herein as incorporated in a liquid fuel cook stove of the stand type. The frame structure may be of any approved form, the one illustrated comprising a top 1, a base 2, and 85 pan 3 which are supported in parallel relation to each other and at suitable distances apart, by legs 5 which, as shown in Fig. 5, are of angular formation. Extending across each end of the stove is a panel 7 which, at 90 its lower end, extends alongside the adjacent end flange 8 of the base 2 and is curled inwardly about the lower edge thereof as best seen in Figs. 6 and 7. A back panel 10 extends from end to end of the stove and 95 from the top 1 to the base 2. The back panel is stiffened at its longitudinal center by a vertical rib 11, and about openings 12 by beads 13. The openings 12 are for the 100 accommodation of rearwardly tilting drums or flues 15 of burner 16 that are supported above a fuel supply pipe 17 sustained by the end panels 7 in a horizontal position a suitable distance above the base 2. The connection between the supply pipe 17 and the 105 end panels 7 is effected through brackets 18 that are secured to the end panels and extend inwardly therefrom and to which the pipe is fastened by clips 19. This is in accordance with well established practice. 110

The burners 16 are shown as connected to the pipe 17 through elbow fittings 20 that are bound to the pipe by clamps 21. This also is common practice and so far as the present invention is concerned may be replaced by any approved means of connecting the burners to the supply pipe so as to establish communication between the burners and the pipe. The supply pipe extends 10 through apertures in the end panels 7 and at the right hand end of the stove is inclined upwardly where it is connected to a distributing receptacle 23 that is partly supported by the supply pipe and partly by 15 a bracket 24 from the adjacent end panel. Hingedly connected at 25 to the receptacle 23 is a carrier 26 for a liquid fuel container 27 that is preferably in the form of a glass bottle. Surmounting the carrier 26 is a 20 shelf 28 that is sustained by a bracket 29 with its top surface in the plane of the corresponding surface of the stove top 1. The carrier 26, together with a shelf 28, is adapted to be swung from the position 25 wherein it is illustrated to an inverted position in front of the receptacle 23. When in the latter position, a part 30 of the carrier rests against a stop 31 that extends from the frame of the stove.

30 By reference to United States Letters Patent Nos. 1,209,811 and 1,448,333, issued December 26, 1916 and March 13th, 1923, respectively, wherein the construction and operation of similar fuel supply systems are 35 illustrated and described, it will be seen that when the carrier 26 is in inverted position the container or bottle 27 may be set into it so that when the carrier is swung to normal position the container or bottle 40 is inverted over the receptacle 23.

Adapted to be supported adjacent the left hand end of the stove is a distributing receptacle 35 to which is hingedly connected at 36 a carrier 37 for a container or bottle 38. 45 These elements are duplicates of the equivalent elements situated at the right hand end of the stove and which have just been described. A bracket 40 connects the receptacle 35 with a cross member 41 that has its 50 ends 42 engaged between the front and rear edge portions of the adjacent end panel 7 and the opposed flanges of the corresponding legs 5. A brace 43 extends downwardly from the central portion of the cross member 41 and then inwardly where its lower 55 end is formed to provide a hook 44 that embraces the lower edge portion of the end panel 7 and the flange 8 of the base 2. A stop 45 extends forwardly and outwardly 60 from the angle of the brace 43 in a position to be engaged by a part 46 of the carrier 37 when the carrier is in inverted position.

A pipe fitting 50 has a branch 51 that is 65 connected to the receptacle 35 and a branch

52 that is projected through an aperture in the brace 43 and beyond which it is threaded for the application of a sleeve 54 arranged to receive the left hand end of the fuel supply pipe 17. The end of the supply pipe 70 is shown in the present case as smooth and as telescoping within the sleeve 54; and a liquid tight joint is effected between the pipe and said sleeve by a gland nut 55 which screws on the sleeve and contains a washer 75 56 of compressible material, as for example, properly treated asbestos. A third branch 57 of the fitting 50 is adapted to be closed by a screw cap 58 which may be removed for the purpose of draining the fuel system. 80

Attention is now called to the fact that overflow openings 60 are formed in the enlarged upper ends of the receptacles 23 and 35; and these openings are in a horizontal plane corresponding to the maximum liquid 85 fuel level within the burners 16, and are somewhat above the normal liquid level within the receptacles. As previously explained, the containers 27 and 38 are liquid sealed and ordinarily the liquid within the 90 receptacles 23 and 35 stands at an elevation very slightly above the mouths of the containers, as shown in Fig. 6.

Assuming that the liquid fuel is at about the elevation indicated in Fig. 6 in both receptacles 23 and 35, under which circumstances the stove would be standing substantially level, the fuel within the burners 16 would be at the same level. Should, through any cause, as by an accidental tilting of one of the containers, a quantity of fuel be discharged into the system sufficient to bring the level therein above the lower edges of the openings 60, the excess fuel would flow out through said openings at 100 105 points so remote from the burners as to create no dangerous conditions, while the liquid level within the burners would not rise above the plane of the lower edges of the openings 60, indicated by the line $a-a$ of Fig. 1, 110 this line representing the maximum liquid fuel level within the burners.

Should the stove be tilted endwise, as by being placed upon an uneven support or by being stood upon a floor that is not level, 115 the liquid fuel within the system will flow to the lower end; and should the angle of inclination be great enough to bring the openings 60 at one end of the stove into a horizontal plane at about, or below, that of 120 the mouth of the container situated at the other end of the stove, the fuel would simply waste through the system, discharging through the lower openings 60 until the contents of the containers is exhausted. 125 Naturally, such a situation would compel the user to level the stove sufficiently to insure satisfactory operation.

While the foregoing embodiment of the invention has in view the provision of 130

means requiring the user to see that the stove or apparatus is practically level and therefore capable of efficient operation, it also has in view a comparatively simple attachment that may be conveniently applied to an oil stove or apparatus for increasing the fuel capacity thereof, such an arrangement obviously making it unnecessary to replenish the oil supply as frequently as in stoves 5 having only one reservoir. Stoves equipped with the auxiliary reservoirs are especially suitable for use in restaurants and like places where the demand on the stove is heavy and practically continuous.

10 The construction of the auxiliary container or reservoir herein illustrated is especially convenient of attachment, it being only necessary to loosen the fastening means which hold the legs and the end panel together sufficiently to permit the parts to separate so that the ends 42 of the cross member 41 may be engaged between said parts, and when the ends 42 are placed inside the flanges of the legs 5, and the hook 44 engaged about the lower edge of the end panel and about adjacent flange of the base 2; the sleeve 54 may be slipped over the end of the pipe 17 and the gland nut 55 screwed up tightly to compress the packing element 30 or washer 56 about the pipe and effectively seal the joint between the pipe and the sleeve.

In instances where the attachment is applied to a stove that originally had had the 35 terminal of its feed pipe threaded and closed by a screw cap, similar to the one indicated at 58, the cap may be removed and the gland nut applied to the threaded end of the pipe precisely as above described, the gland nut 40 slipping over the threads of the pipe and serving to compress the packing washer 56 about said threads. However, in such instances, it may be found preferable to equip the attachment with the form of connection 45 illustrated in Fig. 7 where a relatively small tube 65 extends axially from the branch 52 of the fitting 50 through an aperture in the brace 43 and is adapted to be inserted into the end of the fuel feed pipe 17. A gland nut 66 surrounds the tube 65 and is arranged to be screwed onto the threaded end of the pipe 17 and compress between the end wall of the nut and opposed end surface of the pipe a washer 68 of lead or the like.

55 So far as the overflow feature is concerned, advantages pertaining thereto and attributed to the foregoing embodiment of the invention are attained in the very simple modification illustrated in Figs. 2, 4 and 8.

60 A spout 70 is here employed and it has a lateral branch 71 at its inner end that is engaged over the end of the fuel supply pipe 17 and the end of said branch is reduced and threaded for the application of a gland nut 65 which is arranged to compress a packing

washer or element 73 about the pipe 17 and effectively seal the joint between said pipe and the spout 70, the joint being of such nature as will permit the spout to be turned with respect to the pipe. A bracket 75 is secured, as by bolts 76, to the end panel 7 and its outer end is forked, as shown at 78 in Fig. 10, to embrace the reduced end portion 71 between the inner end of the nut 72 and the shoulder formed by the reduction in diameter of said branch. The bracket serves to prevent movement of the spout lengthwise of the pipe 17 while permitting rotation of the former. The spout is normally held in an upright position by means of a spring 80 tongue or latch 79 which may be formed integral with the bracket 75. When the spout is in upright position its upper end is in substantially the plane of the bottom edges of the overflow openings 60 in the reservoir 85 23, as indicated by the continuation in Fig. 2 of the line a—a of Fig. 1.

When it is desired to drain the system, the spout 70 may be turned downwardly for such purpose.

In Fig. 9 the spout is shown as having a relatively small tube 80 inserted within its lateral branch 71. The tube 80 is adapted to be telescoped within the end of the pipe 17 while a gland nut 82 is screwed onto the 90 threaded end of the pipe to compress a washer 83 of lead or the like about the tube 80 to effectively seal the joint between said tube and the pipe. This modification is substantially the same as that illustrated in Fig. 7 in connection with the first described embodiment of the invention.

In the manufacture of stoves embodying my invention, it is my intention to equip them with the overflow and drain spout, as 100 illustrated in Figs. 2, 4 and 8; and should a purchaser wish to increase the oil capacity of the stove, he may procure the attachment illustrated in Figs. 1, 3, 5 and 6 and substitute it for the spout.

The modifications of the two forms illustrated respectively in Figs. 7 and 9 are for use on stoves which, in the original instance, had their feed pipes threaded and closed by screw caps, similar to cap 58, as hereinbefore 115 described.

Having thus described my invention, what I claim is:—

1. In combination, a liquid fuel burner, a fuel system having connection with the burner so as to supply fuel thereto, and a frame structure supporting the burner and the fuel supply system in fixed relation to each other, said system having overflow openings spaced from the burner on opposite sides thereof and at an elevation corresponding to the maximum fuel level in the burner.

2. In combination, a supporting structure, a liquid fuel feed pipe sustained thereby, a burner connected to said pipe so as 130

- to receive fuel therefrom, and overflow means communicating with the pipe on opposite sides of the burner and having overflow openings at an elevation corresponding to the maximum fuel level in the burner. 5 to the maximum fuel level in the burner. 70
3. In combination, a supporting structure, a liquid fuel reservoir sustained thereby, a burner supported by the structure, a feed pipe leading from the reservoir to a point 10 beyond the burner, the burner having connection with the feed pipe so as to receive fuel therefrom, overflow means connected to the pipe beyond the burner, said means and the aforesaid reservoir having overflow openings at an elevation corresponding to the maximum fuel level in the burner. 15
4. In combination, a supporting structure, a distributing receptacle sustained thereby, a burner supported by the structure, a feed 20 pipe leading from the distributing receptacle to a point beyond the burner, the burner having connection with said pipe so as to receive fuel therefrom, overflow means connected to the pipe beyond the burner, 25 said means and said distributing receptacle having overflow openings at an elevation corresponding to the maximum fuel level in the burner, and a liquid fuel container supported in inverted position over the distributing receptacle and having a discharge mouth extending into the distributing receptacle below the overflow openings thereof and which is adapted to be sealed by an accumulation of fuel within the distributing 35 receptacle. 35
5. In combination, a supporting structure, a liquid fuel reservoir sustained thereby, a burner supported by said structure, a feed pipe leading from the reservoir to a point 40 beyond the burner, the burner having connection with the pipe so as to receive fuel therefrom, and a combined overflow and drain means connected to the pipe beyond the burner, said means and the fuel reservoir 45 having overflow openings at an elevation corresponding to the maximum fuel level in the burner. 105
6. In combination, a supporting structure, a liquid fuel reservoir sustained thereby, a 50 burner supported by the structure, a feed pipe leading from the reservoir to a point beyond the burner, the burner having connection with the pipe so as to receive fuel therefrom, and an auxiliary reservoir connected to the pipe beyond the burner, the auxiliary and the first mentioned reservoirs having overflow openings at an elevation corresponding to the maximum fuel level in the burner. 110
7. In combination, a supporting structure, a liquid fuel reservoir sustained thereby, a burner supported by said structure, a feed pipe leading from the reservoir to a point 55 beyond the burner, the burner having connection with the pipe so as to receive fuel 60
- therefrom, and an attachment adapted to be applied to the supporting structure and incorporating an auxiliary reservoir that is adapted to be connected to the feed pipe, the auxiliary and the first mentioned reservoirs having overflow openings at an elevation corresponding to the maximum fuel level in the burner. 75
8. In combination, a supporting structure, a liquid fuel reservoir sustained thereby, a burner supported by said structure, a feed pipe leading from the reservoir to a point beyond the burner, the burner having connection with the pipe so as to receive fuel 80 therefrom, a member designed for attachment to the supporting structure, an auxiliary reservoir carried by said member, a pipe fitting connected to the reservoir and adapted to align with the feed pipe when said member is attached to the supporting structure, and a connection for securing together and establishing communication between said fitting and the feed pipe, the auxiliary reservoir and the first mentioned reservoir having overflow openings at an elevation corresponding to the maximum fuel level in the burner. 85
9. In combination, a supporting structure, a distributing receptacle sustained thereby, a burner supported by said structure, a feed 90 pipe leading from said receptacle to a point beyond the burner, the burner having connection with the pipe so as to receive fuel therefrom, a bracket for attachment to the supporting structure, a distributing receptacle carried by the bracket, a pipe fitting 95 connected to said receptacle and adapted to align with the feed pipe when the bracket is applied to the structure, a connection for securing together and establishing communication between said fitting and the feed pipe, the distributing receptacles having overflow openings at an elevation corresponding to the maximum fuel level in the burner, and liquid fuel containers above the distributing receptacles and having discharge mouths projecting into said receptacles below the overflow openings thereof and which are adapted to be sealed by an accumulation of fuel within the receptacles. 100
10. In combination, a supporting structure, a distributing receptacle sustained thereby, a burner supported by said structure, a feed pipe leading from said receptacle to a point beyond the burner, the burner having connection with the pipe so as to receive fuel therefrom, a bracket for attachment to the supporting structure, a distributing receptacle carried by the bracket, a pipe fitting connected to said receptacle 115 and adapted to align with the feed pipe when the bracket is applied to the structure, a connection for securing together and establishing communication between said fitting and the feed pipe, said fitting incor- 120
- 125
- 130

porating drain means, the distributing receptacles having overflow openings at an elevation corresponding to the maximum fuel level in the burner, and liquid fuel containers above the distributing receptacles and having discharge mouths projecting into said receptacles below the overflow openings thereof and which are adapted to be sealed by an accumulation of fuel within 10 the receptacle.

11. In combination, a supporting structure, a distributing receptacle sustained thereby, a burner supported by said structure, a feed pipe leading from said receptacle to a point beyond the burner, the burner having connection with the pipe so as to receive fuel therefrom, a member for attachment to the supporting structure, a distributing receptacle carried by the member, 15 a pipe fitting connected to said receptacle and adapted to align with the feed pipe when the member is applied to the structure, a connection for securing together and establishing communication between said pipe fitting and the feed pipe, said pipe fitting incorporating draining means, and liquid fuel containers above the distributing receptacles and having discharge mouths projecting into said receptacles and which are 20 adapted to be sealed by an accumulation of fuel within the receptacles.

12. The combination with a stove structure comprising a top, legs supporting the top, a base sustained by the legs a suitable 35 distance below the top, an end panel extending between the front and rear legs at one end of the stove and situated between the top and the base, a fuel supply pipe supported above the base and extending beyond the end 40 panel, a liquid fuel reservoir wherewith the

supply pipe has connection, and a burner connected to the supply pipe so as to receive fuel therefrom; of an attachment adapted to be applied to the end of the stove, said attachment consisting of a cross member the 45 respective ends of which are adapted to be engaged between the front and rear edges of the end panel and the opposed portions of the adjacent legs, a brace depending from said cross member and designed to embrace 50 the end portion of the base, a liquid fuel reservoir sustained by the bracket, a pipe fitting connected to said reservoir and having a part that aligns with the fuel supply pipe when the bracket is applied to the stove, 55 and a connection through which said pipe fitting and the supply pipe are secured together, the reservoirs having drain openings at an elevation corresponding to the maximum fuel level of the burner. 60

13. In combination, a supporting structure, a distributing receptacle sustained thereby, a burner supported by said structure, a feed pipe leading from said receptacle to the burner, a bracket for attachment 65 to the supporting structure, a distributing receptacle carried by the bracket, the last mentioned distributing receptacle having means for communicatively connecting it with the feed pipe when the bracket is applied to the structure, and liquid fuel containers arranged above, and having discharge mouths projecting into said receptacles and which are adapted to be sealed by an accumulation of fuel within the receptacles. 70

In testimony whereof, I hereunto affix my signature.

LEE S. CHADWICK.
